United States Patent Office.

SEWELL E. JEWETT, OF HAVERHILL, MASSACHUSETTS.

Letters Patent No. 74,227, dated February 11, 1868.

IMPROVEMENT IN OPERATING WINDOW-SHUTTERS.

The Schedule referred to in these Letters Patent and making part of the same.

TO ALL WHOM IT MAY CONCERN:

Be it known that I, SEWELL E. JEWETT, of Haverhill, county of Essex, and State of Massachusetts, have invented a new and useful Improvement in Window-Blind Operators, thereby producing a cheap, durable, and efficient device for that purpose; and I do declare that the following is a full, clear, and exact description of the construction and operation of the same, reference being had to the accompanying drawing, forming a part of this specification; wherein—

A, Figure 1, represents an ordinary window-blind as attached to the window, and it also represents my device for opening and closing the blind, consisting essentially of the following parts: Knob K, interior and exterior escutcheons E and E', slotted connecting-bar B, concave cam C, vibrating-pin P, and lever-plate L. Said lever-plate being firmly secured to the blind, connects the whole device therewith. Fig. 1 represents the blind as closed and fastened by slotted bar B engaging with interior escutcheon E.

To open the blind, raise knob K sufficiently to release slot S from escutcheon E; then, by giving knob K a sudden inward motion, cam C is brought to bear upon pin P. The blind yielding to this pressure is thrown one half way open, its momentum carrying it past the centre, bringing pin P into a position relative to the projecting point J of cam C, as shown in Figure 2. Knob K, being now pressed outward, throws the blind entirely open, and fastened by slot S again engaging with interior escutcheon E.

It is plain that by reversing the above operation the blind will be closed and fastened.

Claim.

1. I claim the peculiar construction of cam C, especially with reference to the projecting point J, as shown in fig. 2, when applied to and used for the purpose of opening and closing a window-blind.

2. I claim, in combination with said cam C, knob K, interior and exterior escutcheons E and E', slotted connecting-bar B, vibrating-pin P, and lever-plate L, all operating as specified, and for the purpose as set forth,

SEWELL E. JEWETT.
